US0D1069628S

(12) **United States Design Patent** (10) **Patent No.:** **US D1,069,628 S**
(45) **Date of Patent:** **** Apr. 8, 2025**

(54) **LIGHTING FIXTURE**

(71) Applicant: **EMERGENCY TECHNOLOGY, INC.**, Hudsonville, MI (US)

(72) Inventors: **Eric Asselin**, Holland, MI (US);
Brandon Jacobsen, Hamilton, MI (US)

(73) Assignee: **Emergency Technology, Inc.**,
Hudsonville, MI (US)

(**) Term: **15 Years**

(21) Appl. No.: **29/868,306**

(22) Filed: **Nov. 29, 2022**

(51) **LOC (15) Cl.** **10-05**

(52) **U.S. Cl.**

USPC **D10/114.8**

(57) **CLAIM**

The ornamental design for a lighting fixture as shown and described.

DESCRIPTION

FIG. 1 is a downward-facing perspective view of a lighting fixture, showing our new design;

FIG. 2 is an upward-facing perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof; and,

FIG. 8 is a right side view thereof.

Portions of the lighting fixture are shown in broken lines. Portions shown in broken lines form no part of the claimed design.

1 Claim, 8 Drawing Sheets
